DESIGN FOR A BUILDING BLOCK OR SIMILAR ARTICLE

Fred E. Poortinga, Willmar, Minn., assignor to Redfield Brick & Tile Company, Redfield, Iowa, a co-partnership consisting of William J. Goodwin, Sr., Grace K. Goodwin, William J. Goodwin, Jr., Robert K. Goodwin, William A. Queale and Dale C. Chance

Application December 27, 1937, Serial No. 73,873

Term of patent 7 years

To all whom it may concern:

Be it known that I, Fred E. Poortinga, a citizen of the United States and a resident of Willmar, in the county of Kandiyohi and State of Minnesota, have invented a new, original, and ornamental Design for a Building Block or Similar Article, of which the following is a specification, reference being had to the accompanying drawing, forming part thereof.

Figure 1 is a perspective view of a building block showing my new design; and

Figure 2 is an end elevational view thereof on an enlarged scale.

I claim:

The ornamental design for a building block or similar article substantially as shown.

FRED E. POORTINGA.
